STOVE

Original Filed Jan. 20, 1925

UNITED STATES PATENT OFFICE.

HARLAN M. BRITAN, OF OJUS, FLORIDA.

STOVE.

Original application filed January 20, 1925, Serial No. 3,659. Divided and this application filed February 23, 1926. Serial No. 90,183.

This invention relates to an improvement in oil stoves or the like and has for its object the provision of a stove wherein heat is efficiently generated with economy in the 5 consumption of fuel and safety in the operation of the burner.

Another object resides in the provision of a burner having the advantages and capacities enumerated and which is susceptible of 10 convenient and graduated control and also of simple and durable construction, reliable and safe in use and easy and comparatively inexpensive to manufacture.

Other objects and advantages reside in certain novel features of the construction, arrangement of parts which will be herein-after more fully described and particularly pointed out in the appended claims, reference being had to the accompanying drawings forming a part of this specification, and in which:—

Figure 1 is a fragmentary perspective view showing one embodiment of the invention,

25 Figure 2 is a view thereof in central longitudinal vertical section,

Figure 3 is a view thereof in transverse vertical section on line 3—3 of Figure 2,

30 Figure 4 is a detail perspective view of the plug of the burner, and

Figure 5 is a detail sectional view of the oil inlet pipe.

Referring to the drawing, the numeral 1 designates generally an oil stove which has 35 a lower shelf 2 supported on legs 3, sides 4, a top 5 and a back 6. Of course the structure of the stove thus far described may be varied. A plurality of lids two of which are shown and designated at 7 and 8 are provided and supported on the top of the stove, the lids being fitted in openings provided for the same in the top and having ribs 11 which engage the top around the openings to support the lids in position. The lids are 45 of substantially annular form and each has an inwardly inclined or beveled top wall 12 adapted to support cooking utensils of various sizes in such manner that the base of the cooking utensils closes the opening defined 50 by the annular lid in the top of the same. The structure of these lids and the manner in which they communicate with each other forms the subject-matter of my co-pending application, filed Jan. 20, 1925, Serial No.

3,659 and of which the present case is a division. 55

Means is provided for supplying heat to the lid 10 and this means includes a burner having a cup member 13 supported at the upper end of an oil inlet pipe 14. The upper 60 end of the oil inlet pipe 14 is threadedly connected with the base of the cup member 13 at its center and projects above the bottom of the base so that dirt and sediment will be deposited on the bottom of the base and will 65 not fall back into the oil inlet pipe. The pipe 14 is filled up with wires so as to restrict the quantity of oil to the amount necessary to supply the requirements of the burner. In lieu of the wires a rod which is smaller 70 than the bore of the pipe may be fitted in the pipe.

As shown in Fig. 5 the burner pipe 14 has a filler rod 14^a provided therein to define a restricted passage 14^b for the fuel. In lieu 75 of the fuel rod 14^a the pipe 14 may be filled with wires and the interstices to the wires provide the restricted passage for the fuel.

By restricting and retarding the flow of the fuel through the burner pipe to the amount 80 necessary to proper combustion safety in operation is assured. The interstices between the wires or the interstice between the rod and the pipe provide the passageway for the oil. This feature is one of safety and prevents 85 conflagration or explosion. A plug 15 which has an apertured plug 15^a to facilitate handling, is set in the cup member 13 and has an opening 16 centrally of its base to receive the upper end of the oil inlet pipe 14. Slots 90

17 are also provided in the base of the plug and extend from the opening 16 to the periphery of the plug. The plug 15 is somewhat smaller than the cup member 13 to provide a wick receiving space 18 in which a 95 wick 19 is fitted. The upper end of the plug 15 is reduced to provide a shoulder 19' on which a combined wick holder and chimney support 20 rests. The combined wick holder and chimney support 20 comprises an inner

perforated sleeve 21 and an outer perforated sleeve 22 between which the wick 19 is fitted. The sleeve 22 carries spider arms 23, the outer ends of which are connected to the lower section 24 of the chimney designated 100 generally at 25 and made up of the section 24 and a section 26 connected with the lid 8.

Between the sections 24 and 26 a sleeve 27 of 105

asbestos is provided. As shown in Figs. 2 and 3 the lower end of the section 24 is spaced from the cup member 13 to provide the air inlet around the burner and upper end of the chimney extends through the open bottom of the lid 8.

A casing, designated generally at 30, encloses the burner and chimney and may consist of sheet metal sections 31 and 32 between which a layer 33 of asbestos is disposed. The asbestos is extended over the upper edges of the sections 31 and 32 and engages the underside of the top 5 of the stove. The section 31 is adjustably supported as at 34 on the shelf 2 of the stove and the section 32 is carried on the section 31. A hinged door 35 is incorporated in the section 31. By adjusting the section 31 the top of the casing may be pressed firmly against the underside of the top 5 and prevent the escape of the warm air or gases, thereby enhancing the efficiency of the stove to a very material extent.

The oil is supplied through the inlet pipe 14 through a supply line 40 from a tank 41 in which a safety oil feed connection 42 forming the subject-matter of my co-pending application, Serial No. 202,937, is embodied. In this supply line 40 a control valve 43 is also embodied and has an angular finger 44 fixed to the axis of the hand wheel 45 by which the valve is adjusted. This finger 44 co-acts with a bracket 45 having a curved portion 47 bearing numbers 48

so that the adjustments of the valve may be made with precision. A stop lug 49 is integrally formed with the bracket 46 and limits the turning movement of the valve to such position as to supply the minimum amount of oil necessary to keep the burner 40 lighted. A shut off valve 50 is also incorporated in the supply line.

I claim:

1. In a stove, a burner including an oil cup, a plug within the oil cup defining a wick receiving space, said plug having means thereon for supporting a wick holder and chimney, a wick in said wick holder, and means comprising oppositely disposed perforated sleeves for closely engaging and supporting said wick.

2. A stove structure including an oil cup, an oil supply pipe leading to said cup and projecting vertically through the bottom thereof, a recessed plug resting in the cup, the recesses of said plug registering with the orifice of the supply pipe, a shoulder on said plug, and a combined wick holder and chimney support resting upon said shoulder.

3. In a stove, a burner comprising an oil cup, a plug in said cup defining a wick space, a shoulder upon said plug, a combined wick holder and chimney support resting upon said shoulder, a wick held by said holder and closely engaged and protected by oppositely disposed perforated sleeves, and a sectional chimney supported by said holder.

HARLAN M. BRITAN.
